UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

MACHINE FOR PERFORATING RIM LUGS

Application filed April 3, 1926. Serial No. 99,638.

The invention relates to machines for perforating rim lugs and refers more particularly to machines for perforating clamping lugs attached to a demountable rim. One of the objects of the invention is to provide a machine for holding the rim true to size and shape and perforating the attached lugs while the rim is thus held. Another object is to trim the lugs at substantially the same time they are perforated. A further object is to provide the machine with means for facilitating the withdrawal of the lug perforating means from the lugs.

With these as well as other objects in view, the invention resides in the novel features of construction and combinations and arrangements of parts as more fully hereinafter set forth.

This application contains subject matter also found in my co-pending application Serial No. 80,636, filed January 11, 1926, upon Method of making tire carrying rims.

In the drawings:

Figure 1 is a plan view, partly in section, of a machine embodying my invention;

Figures 2 and 3 are cross sections on the lines 2-2 and 3-3, respectively, of Figure 1, Figure 3 showing in elevation the lower portion of the rim ejector mechanism;

Figures 4 and 5 are cross sections on the lines 4-4 and 5-5 of Figure 3;

Figure 6 is a side elevation of a demountable rim having permanently secured thereto the unfinished clamping lugs;

Figure 7 is a similar view with the clamping lugs finished.

The machine embodying my invention is designed particularly for use in perforating and trimming clamping lugs permanently attached to demountable rims. 1 is the demountable rim and 2 the clamping lugs which have been permanently secured thereto. These clamping lugs, as shown in Figure 6, are unfinished, while as shown in Figure 7, they are finished, having been perforated and trimmed.

The machine is in the nature of a press having the bolster plate 3 and the vertically reciprocable holder member 4, which is adapted to be secured to the ram of the press,

For sizing and shaping the rim 1, I have provided the combined sizing and shaping blocks 5 which are engageable with the inner face of the rim and are movable radially outwardly to the proper distance to effect a predetermined sizing and shaping of the rim. For radially moving the blocks outwardly, I provide suitable means for actuating these blocks from the reciprocable holder member 4. As shown, 6 is a central depending projection upon the holder member 4 and having secured to its sides the wear plates 7 which have cammed outer faces for engaging the rollers 8 carried upon the radial inner ends of the blocks 5. Alternate blocks 5 carry the dies 9 which in addition to being engageable with the inner face of the rim are engageable with the inner sides of the clamping lugs 2 to support the same. For returning the blocks 5 radially inward, those carrying the dies 9 are engaged by the plungers 10 which are yieldably forced radially inward by means of the coil springs 11 surrounding the plunger shanks and located within the housings 12, while the other blocks are engaged by the coil springs 11.

For finishing the lugs 2, I provide means controlled by the reciprocable holder member 4 and engageable with the lugs after the combined sizing and shaping blocks have been forced radially outward to bring the rim to true size and shape. In detail, 13 are punches engageable with the lugs and cooperating with the dies 9 to perforate the lugs, the dies supporting the lugs and having vertical bores 14 into which the lower ends of the punches may enter. These punches 13 are carried by the punch holders 15 which in turn are secured to the lower side of the holder member 4 and the punches are so located upon the holder member that they engage the lugs after the cammed outer faces of the wear plates 7 have forced the combined sizing and shaping blocks 5 radially outward to their outermost positions. For trimming the lugs there are the trimming punches 16 which are also secured to the punch holders 15 and are adapted to cooperate with the upper inner corners of the dies 9 to shear the exposed edge portions of the 100

lugs. These trimming punches are preferably engageable with the lugs at substantially the same time as the perforating punches.

5 To provide for removal of the material sheared from the lugs in trimming the same there is a space 17 surrounding the inner faces of the dies and for guiding the trimming punches there are wear plates 18 secured to the combined sizing and shaping blocks 5 and engageable with the inner faces of these trimming punches.

10 To clamp the lugs against the dies prior and subsequent to the engagement of the perforating and trimming punches with the lugs, I have provided the clamp 19 surrounding each perforating punch 13 and having its lower end engageable with the outer face of a lug. Each of these clamps is yieldably

15 forced downwardly by means of the coil springs 20 carried upon the holder member 4 and engageable with one end of the rock arm 21 which is pivotally mounted at 22 upon the holder member. The other end of this 20 rock arm is engageable with the plate 23 to which is secured the depending ejector rods 24 which extend downwardly through and are guided by the holder member and alongside the perforating punch and have their 25 lower ends engageable with the upper end of the clamp. With this arrangement it will be seen that the clamps act both to clamp the lugs against the dies prior to engagement of the perforating and trimming punches with

30 the lugs and to hold the lugs against the dies during the return strokes of the perforating and trimming punches, thereby facilitating withdrawal especially of the perforating punches. For ejecting the rim 1 after the 35 lugs 2 have been finished by perforating and trimming the same, I have provided the ejectors 25 in the nature of blocks which are engageable with the lower edge of the rim after the holder member 4 has been carried

40 upwardly by the rim and the combined sizing and shaping blocks have been moved radially inward by means of their coil springs. These ejectors are carried by the rods 26 which extend upwardly through the bolster plate 3 and are secured to the bars 27 located below the bolster plate. 28 is a rod secured to the bolster plate and depending therefrom for guiding the bars 27, and 29 is a bushing sleeved upon this rod and adapted to be

45 raised by means of the foot pedal 30 which is pivotally mounted upon the bracket 31 carried by the support 32, this latter also being mounted upon and carried by the rod 28. 50 For stamping one of the lugs 2 with suitable indicia such as the mark of the manufacturer, I have provided the stamp 33, which is secured to one of the punch holders 15 and is engageable with the outer side of a lug to

55 imprint thereupon the indicia, this stamp

being engageable with the lug just after the lug has been apertured and trimmed.

What I claim as my invention is:

1. In a machine for perforating lugs attached to a rim, the combination with means for holding the rim true to size and shape, of means for perforating the attached lugs while the rim is held true to size and shape. 70

2. In a machine for perforating lugs attached to a rim, the combination with means movable radially to size and shape the rim, of means subsequently movable transversely of the lugs to perforate the same while the rim is sized and shaped. 75

3. In a machine for perforating lugs attached to a rim, the combination with radially movable sizing and shaping blocks engageable with the rim to size and shape the same, of punches movable transversely of the lugs for perforating the lugs while the rim is sized and shaped. 80

4. In a machine for perforating lugs attached to a rim, the combination with radially movable means for sizing and shaping the rim, of means movable transversely of the lugs to perforate the same while the rim is sized and shaped and a reciprocable member for actuating said sizing and shaping means and perforating means in timed relation. 85

5. In a machine for perforating lugs attached to a demountable rim, the combination with radially movable sizing and shaping blocks engageable with the rim to size and shape the same and dies upon certain of said blocks engageable with the lugs, of punches movable transversely of the lugs adapted to cooperate with said dies to perforate the lugs while the rim is sized and shaped. 90

6. In a machine for perforating lugs attached to a demountable rim, the combination with rim sizing and shaping blocks movable radially outward into engagement therewith and dies carried by certain of said blocks for engaging the lugs, of a reciprocable member, means upon said member for radially moving said blocks outwardly, punch holders upon said member and punches carried by said holders adapted to cooperate with said dies to perforate the lugs while the rim is sized and shaped. 100

7. In a machine for perforating lugs attached to a rim, the combination with means for holding the rim true to size and shape, of means for perforating and trimming the attached lugs while the rim is held true to size and shape, and a member surrounding said perforating means and yieldably engaging the lugs for clamping the same in place. 110

8. In a machine for perforating lugs attached to a rim, the combination with radially movable blocks engageable with the rim to size and shape the same and dies carried by certain of said blocks for engaging the lugs, punches movable in a direction trans- 125

verse to the direction of movement of the sizing blocks for cooperating with said dies to perforate the lugs and transversely movable trimming punches for cooperating with said trimming punches for cooperating with said dies to trim the lugs.

9. In a machine for perforating lugs attached to a rim, the combination with means holding a rim true to size and shape, of means movable transversely of the lugs to perforate the same and means cooperating with said perforating means to facilitate the withdrawal of said perforating means from the lugs.

10. In a machine for perforating lugs attached to a rim, the combination with means for holding a rim true to size and shape, of punches for perforating the attached lugs while the rim is held true to size and shape and means engageable with the lugs prior and subsequent to engagement of said punches with the lugs for holding the lugs in place and facilitating withdrawal of said punches.

11. In a machine for perforating lugs attached to a rim, the combination with means for holding a rim true to size and shape, of a reciprocable member, punches carried by said member for engagement with the lugs to perforate the same and means carried by said member for resiliently engaging the lugs prior and subsequent to engagement of said punches therewith for clamping the lugs in place and facilitating withdrawal of said punches.

35 12. In a machine for perforating lugs attached to a rim, the combination with means for holding a rim true to size and shape, of a reciprocable member, punches carried by said member for perforating the lugs, clamps adjacent to said punches and engageable with the lugs prior and subsequent to engagement of said punches therewith and spring pressed means carried by said member for actuating said clamps.

45 13. In a machine for perforating lugs attached to a rim, the combination with means for holding a rim true to size and shape, of a reciprocable member, punch holders carried by said member, punches carried by said holders and engageable with the lugs to perforate the same, clamps surrounding said punches and engageable with the lugs prior and subsequent to engagement of said punches therewith, springs carried by said member, rock arms pivotally mounted upon said member and rods actuated by said rock arms and engageable with said clamps.

60 14. In a machine for perforating lugs attached to a rim, the combination with means for holding a rim true to size and shape, a reciprocable member, punch holders carried by said member, punches carried by each of said holders for respectively perforating and trimming the lugs, clamps surrounding the perforating punches, springs carried by said

member, rock arms pivotally mounted upon said member and reciprocable rods engageable with said clamps and actuated by said rock arms.

15. In a machine for perforating lugs attached to an annular tire carrying rim, the combination with means for holding the rim true to size and shape, of means for perforating and trimming the attached lugs while the rim is held true to size and shape.

In testimony whereof I affix my signature.

WILLIAM N. BOOTH.
